[57] CLAIM

The ornamental design of an upright extractor, as shown and described.

DESCRIPTION

FIG. 1 is a perspective view of an upright extractor showing our new design;

FIG. 2 is a first side elevational view thereof;

FIG. 3 is a right side elevational view thereof;

FIG. 4 is a rear elevational view thereof;

FIG. 5 is a left side elevational view thereof;

FIG. 6 is a bottom plan view thereof; and,

FIG. 7 is a top plan view thereof.

The details shown in broken lines in FIGS. 1, 3-5 are shown for illustrative purposes only and form no part of the claimed design.

1 Claim, 5 Drawing Sheets
